ATTORNEY

UNITED STATES PATENT OFFICE.

ROBERT C. STURGES, OF GLOVERSVILLE, NEW YORK.

CHILD'S AUTOMOBILE CHAIR.

Application filed November 25, 1927. Serial No. 235,654.

The chair or seat of the present invention, while capable of a wide range of utility, is primarily intended for use as a portable device for comfortably supporting an infant 5 or small child in an automobile.

An object of the invention is to provide a chair which may be maintained in proper anchored position by the weight of an adult, and which will dispose the child directly 10 over the lap of the person anchoring the chair in such a position that the wants of the child may be readily attended to, and yet, the attendant be completely relieved from the child's weight.

15 A further object of the invention is to provide a chair of this character which will provide a comfortable seat for a child, while relieving an attendant from the inconveniences and discomforts of holding the child 20 on the lap during an automobile journey.

Other objects of the invention are to provide a chair of simple, practical construction, which will be rugged, durable and efficient in use, neat and attractive in appearance, and well suited to the requirements 25 of economical manufacture and convenient portability.

With the above noted and other objects in view, the invention consists in certain 30 novel features of construction and combinations and arrangements of parts, as will be more fully hereinafter set forth and pointed out in the claims. The invention may be more fully understood from the following 35 description in connection with the accompanying drawings, wherein—

Fig. 1 is a perspective view of a chair embodying the present invention, part of the cover being broken away to expose the 40 frame.

Fig. 2 is a somewhat diagrammatic view showing the chair in side elevation, and indicating in dot and dash lines the relative position of an automobile seat and the body 45 of an adult anchoring the chair.

Fig. 3 is a front elevational view of the device.

The device consists essentially of a skeleton platform 10 preferably formed by looping a length of wire into general rectangular shape. A standard indicated generally at 50 11 rises from the center of one side of the platform and supports a seat indicated generally at 12; this seat being carried at one

side by the standard 11 and disposed over 55 the platform 10 at a sufficient height to accommodate the thigh of an adult between the platform and seat.

In use, the adult sits on the platform 10, or at least one leg overlies the platform 60 10, pressing the same into the automobile cushion as best seen in Fig. 2, and disposing the seat 12 immediately over the lap of the person sitting on the platform.

It will be noted that the platform 10 and 65 the seat 12 are not in parallelism, but their planes diverge from the standard 11 outwardly. This angular formation is primarily designed to permit the free edge of the platform to be pressed somewhat into 70 the seat of the car when in use, and dispose the seat 12 in substantial horizontal position. This angular relationship of the platform and seat also accommodates for any slight bending of the seat relatively to the 75 standard due to the weight of a child thereon.

Within the scope of the present invention, 80 various designs of platform standards and seats might be used, and the particular construction herein shown is illustrative of merely one form of the invention in which the entire platform standard and chair frame are bent from a single length of wire.

After forming the loop-like platform 10, 85 the wire ends are turned upwardly together providing a standard of two thicknesses of wire, these wire runs being preferably encircled by a metal sleeve 13 to prevent their relative separation. At the top of the 90 standard, one wire is bent at right angles, and forms a rearwardly extending run 14 cooperating with a forwardly extending run 15 of the other wire to define one arm of the seat. The wire after forming the run 95 14 is bent laterally at right angles, producing a rear cross bar 16, the extreme end of which is turned forwardly and terminates in a run 17 constituting part of the opposite seat arm. The end of the wire run 17 abuts the end of a run 18, the latter corresponding 100 to the run 15 of the opposite chair arm. The runs 15 and 18 of wire are integral with forwardly and downwardly inclined lengths of wire 19, the lower ends of which are 105 united by a forward cross piece 20.

A single length of flexible material, such for instance as leather, is cut to provide a

seat portion 21, side portions 22 and back portion 23. The forward edge of the seat is wrapped around the forward cross bar 20, and secured by rivets 24. The upper 5 ends of the sides 22 are wrapped around the two arms of the chair and secured by similar rivets; while the upper edge of the back 23 is folded over the cross bar 16 and similarly riveted.

10 Instead of rivets, it will be apparent that detachable fastener elements, such as snap fasteners might be utilized, and removable washable covers employed.

Obviously, various changes and alterations 15 might be made in the general form and arrangement of the parts described without departing from the invention. Hence I do not wish to limit myself to the details set forth, but shall consider myself at

liberty to make such changes and alterations 20 as fairly fall within the spirit and scope of the appended claims.

I claim:

A child's seat of the class described including a platform adapted to be anchored by a weight thereon, a standard rising from one side of the platform, and a seat supported at one side by the standard and disposed over and well above the platform, said seat including a skeleton wire frame, said platform comprising a skeleton wire frame, both frames being integral with the standard, said standard comprising a double run of wire encircled by a metal retaining sleeve. 25

Signed at New York, in the county of New York, and State of New York, this 22nd day of November, A. D. 1927.

ROBERT C. STURGES.
